SLIDE FASTENER

Howard Bonbright, Grosse Pointe, Mich.

Application October 3, 1940, Serial No. 359,439

16 Claims. (Cl. 24—205.5)

This invention relates to a slide fastener device or hookless fastener adapted for application to and use with articles of wearing apparel, or the like, to close openings or plackets in said articles. The device of the present invention is not necessarily limited to such use since it is capable of securing together the adjacent edges of pieces of flexible material of various kinds.

One of the objects of the present invention is to provide an improved slide fastener in which the interengaging fastener elements or interlocking teeth members thereof while being manipulated to close the fastener, cannot come in contact with or accidentally engage garments or other articles or material located adjacent to or which underlie that to which the fastener device is attached.

Another object of the invention is to provide an improved fastener of the foregoing character which has the safety feature of preventing its interlocking parts from coming into contact with or seizing and causing damage to articles or material underlying that to which the fastener is applied.

A further object is to provide an improved fastener of the foregoing character having a safety device or garment deflector guard in which the guard lies substantially in the plane of the body portion or slide member of the fastener when the interfitting parts of the fastener are in locked condition.

Another object of the invention is to provide an improved slide fastener device having the safety feature as aforesaid to prevent seizure of material underlying the fastener elements and in which the underside or face of the body portion or slide member may be made relatively flat and smooth.

The foregoing and other objects and advantages of the invention will appear from the following description and appended claims when considered in connection with the accompanying drawing forming a part of this specification, wherein like reference characters designate corresponding parts in the several views.

In said drawing:

Fig. 1 is a fragmentary top plan view or front elevation illustrating one application of the present invention to an article of wearing apparel.

Fig. 2 is a fragmentary bottom plan view or rear elevation of the device of Fig. 1, with the under garment or article of apparel removed.

Fig. 3 is an enlarged vertical sectional view taken substantially along the line 3—3 of Fig. 1, 55

looking in the direction of the arrows, with the parts of the fastener device in locked position.

Fig. 4 is a view similar to Fig. 3 but showing the fastener parts in unlocked position; and

5 Figs. 5 and 6 are views similar to Fig. 3, showing modified forms of fastener devices embodying the present invention.

Before explaining in detail the present invention it is to be understood that the invention 10 is not limited in its application to the details of construction and arrangement of parts illustrated in the accompanying drawing, since the invention is capable of other embodiments and of being practiced or carried out in various ways. 15 Also it is to be understood that the phraseology or terminology employed herein is for the purpose of description and not of limitation, and it is not intended to limit the invention claimed herein beyond the requirements of the prior art.

Slide fastener devices, hookless fasteners or "zippers," as they are sometimes referred to, have come into wide use, especially in connection with garments or articles of wearing apparel. Such devices are, generally speaking, satisfactory.

20 All such fasteners heretofore known, however, have had the objectionable feature of becoming jammed by reason of the fact that garments or other materials which underlie those to which the fastener is attached, come into contact with and are caught by the fastener elements or interfitting teeth of the device when the slide member is manipulated to lock the fastener. This is not only a disadvantage from the standpoint of making it difficult to close the fastener but also because, once an article of clothing or the like is caught between the teeth or jaws of the fastener device, it is impossible to release it without tearing or cutting the material. This causes not only inconvenience to the user but the damage to

30 the apparel is quite considerable, necessitating repairs and often replacement of the articles so damaged. Moreover, where the garment or article of apparel is of the character which is to be worn next to the body of the wearer, such as a

35 foundation garment of fine texture, injury has been caused to the wearer due to the fact that in closing the fastener, the fastener elements or teeth thereof have seized and torn the flesh of the wearer. This is an extremely dangerous condition which exists with all known fasteners of the slide or hookless type.

40 Ladies' shops and the like are constantly receiving complaints from customers who, while trying on a garment having a slide fastener, damage one of their under garments by virtue of

catching it between the jaws of the teeth or fastener elements of the slide fastener on the store garment.

It is, therefore, one of the important features of the present invention to provide an improved safety slide fastener which entirely overcomes the foregoing objectionable and dangerous features of previously known slide or hookless fasteners.

Referring now particularly to Figs. 1 to 4 inclusive of the drawing, there is shown one form of the present embodiment of the invention applied, merely by way of example, to the outer garment or article of wearing apparel, such as a lady's dress. The dress or other outer garment of these figures is shown at A and is divided at a predetermined point to provide an opening or placket B.

Underlying the dress or garment A is another garment or article of wearing apparel C, such as a slip or other undergarment.

The slide fastener device or hookless fastener of the present form of the invention comprises, as shown, two series of separable interfitting and interlocking staggered fastener elements or teeth 10 and 11, each of which may be attached to a separate strip of tape or other fabric (not shown) which is stitched or otherwise attached to the under face of the garment A at the opposed longitudinal edges thereof to define the opening or placket B. The device also comprises a U-shaped slide member or body portion 12, which, as shown, flares outwardly to provide a wider diameter at its forward or lead end 13 than at its inner or following end 14. The slide or body member 12 has a pair of longitudinal grooves or channels formed therein and as seen in Figs. 3 and 4, is substantially U-shaped. This slide member thus receives the two sets or series of teeth or fastener elements 10 and 11 in the grooves or channels thereof and serves to interengage and lock them together and/or separate or disengage them, dependent upon which way the slide is moved relative to the supporting material.

As seen in Fig. 2, the back face or underside 15 of the slide member may be of similar shape or configuration to its front face or upper side, shown in Fig. 1.

The slide member 12 is provided with an operating member or handle shown as a whole at 16. This member 16 may be somewhat longer than the slide 12 and as clearly seen in Figs. 1 and 3, projects considerably beyond its inner or following end or edge 14. The handle or operating member 16 is also extended beyond the forward or lead end 13 of the slide to provide, as shown, an integral extension forming a deflector guard, plow or lead end portion 17 which is curved around the end of the slide toward the back face 15, see Fig. 2. The terminal end of the guard 17 is reduced or narrowed in width to provide a hinge projection 17a fitting between two spaced ears 19 extended forwardly from the slide and arranged at their under sides substantially flush with the back face 15 of the slide as shown in Figs. 3 and 4. The projection 17a may have lateral pin formations (not shown) extending through apertures in the ears 19 to hinge the handle 16 to the slide, or the projection 17a may be pierced transversely to receive a separate hinge pin (not shown) extending therethrough and through the apertures in the ears 19.

The handle member is provided with a penetrating locking spur or lug 22 which, when the

handle member or tab 16 is in the position of Figs. 1 and 3, extends through an opening 9 in the slide member 12 and engages between a pair of adjacent teeth of the series 10 to hold the slide fastener in position against sliding movement relative to the garment A.

As clearly seen in Fig. 4, when the handle member 16 is raised preparatory to shifting the slide, the deflector guard 17 is shifted transversely to the plane of engagement of the fastener elements and rearwardly of said plane to contact and push back or away the underlying material or garment C and displace it sufficiently to prevent it from becoming caught by the fastener elements or teeth 10 and 11 of the slide fastener. Thus, the slide can now be operated with safety and without the hazard or danger of contacting or grabbing the underlying material.

Referring now to Fig. 5, there is shown a somewhat modified form of the fastener embodying the present invention. In this form of the invention the slide member or body portion of the device is shown as a whole at 120 and is provided at its upper end with an annular rib 161. The slide has a back wall or under face 150 which is connected with the front face of the slide by means of an integral end wall or web member 121. The forward end of the member 150 is provided with ears 151. As in the preceding form of the invention, the slide member is of substantially U-shape and is provided with a pair of grooves or channels to receive the fastener elements or teeth 10 and 11. An operating handle or tab, shown as a whole at 160, is provided for moving the slide member. The forward end of the handle member 160 is provided with an annular rib 162 and adjacent the forward end, the member 160 is provided with a hinge member or projection 159. The device of the present form includes also a deflector guard, plow or lead member, shown as a whole at 170. The handle member or tab 160 is hingedly connected with the member 120 by means of a pin 163 which extends through openings formed in the projection 161 and in the hinge projection 159 of handle 160. The deflector guard 170 is pivotally attached to the annular projection 162 by means of a pin 171. This guard member extends rearwardly in spaced relation to the end wall 121 of the slide member and its opposite end extends between and is pivotally connected to the ears 151. The handle member 160 is provided with a spur or lug 122 similar to the spur 22 of the preceding form of the invention. As shown in dotted lines, when the handle member 160 is lifted upwardly, it pivots about the pivot pin 163 whereupon the guard member 170 pivots about its connecting pivots and assumes the position in which it is shown in dotted lines. Thus, when handle 160 is lifted to operate the slide the guard 170 is shifted transversely to the plane of engagement of the fastener elements and rearwardly thereof to deflect or push aside the underlying material C and prevent its being caught between the fastener elements. When the parts are in the full line position, the spur or lug 122 engages between a pair of adjacent fastener elements to hold the parts in locked position against movement relative to the garment.

Fig. 6 of the drawing shows a somewhat further modified form of a slide fastener device embodying the present invention. In this form, there is shown a substantially U-shaped slide member or body portion indicated as a whole at 320. This member is provided with a forward wall or web

member 321 and with a back wall or face 350. The end wall or web member 321 is provided with a narrow hinge projection 323.

The device of the present form of the invention is provided with an operating handle or tab member, shown as a whole at 360. The inner face of the handle member carries a spur or stud 322 similar to the studs or spurs shown in the preceding forms of the invention. The inner face of the member 360 is likewise provided adjacent its forward end with a projecting hinge portion 361. The ends of the hinge projection 361 are preferably in the form of perforated ears which embrace with the projection 323 formed on the end wall 321. The handle member is assembled with the slide member 320 by means of a transversely extending hinge pin 362 which pivotally connects the ears on the projection 361 with the member 323. The handle member 360 at its forward end is extended and provided with an inwardly or rearwardly curved nose 370 which provides the deflector guard or plow of the device. It will be seen that this guard member 370 is spaced forwardly of the end wall 321 and projects into the space between the fastener elements or teeth 10 and 11. When it is desired to slide the fastener relative to the fastener element and the garment upon which they are attached, the handle member 360 is lifted or raised and will pivot about the pivot pin 362 to force the deflector guard or lead member 370 to contact with the underlying fabric C. This movement pushes the fabric C back so as to displace it sufficiently to prevent it from becoming caught by the teeth or fastener elements 10 and 11, when the slide member is operated. This last described position of the parts is indicated in broken lines in Fig. 6.

From the foregoing, it will be seen that I have provided several forms embodying the present invention, each of which has the feature of providing a safety guard or deflector member for the purpose of displacing fabric adjacent to and underlying the slide fastener so as to prevent it from becoming engaged by the fastener elements or teeth of the device. This prevents any possibility of tearing or damaging the underlying fabric and facilitates the easy movement or operation of the fastener device.

I claim:

1. A slide fastener device comprising two series of mating fastener elements adapted to be secured along opposed edges of material to be joined together, a slide shiftable along said edges to engage said elements, and means movable with the slide and shiftable in a direction transverse to the plane of engagement of said elements and rearwardly of the plane of the inner face of the slide a substantial distance whereby to deflect underlying material out of the path of said elements.

2. A slide fastener device comprising two series of mating fastener elements adapted to be secured along opposed edges of material to be joined together, a slide shiftable along said edges to engage said elements and means carried by said slide and shiftable in a direction transverse to the plane of engagement of said elements and rearwardly of the plane of the inner face of the slide a substantial distance whereby to deflect underlying material out of the path of said elements.

3. A slide fastener device comprising two series of mating fastener elements adapted to be secured along opposed edges of material to be joined together, a slide shiftable along said edges to engage said elements, and means pivotally con-

nected to said slide and shiftable in a direction transverse to the plane of engagement of said elements and rearwardly of the plane of the inner face of the slide a substantial distance whereby to deflect underlying material out of the path of said elements.

4. A slide fastener device comprising two series of mating fastener elements adapted to be secured along opposed edges of material to be joined together, a slide shiftable along said edges to engage said elements, and a shiftable handle connected to said slide, said handle having a guard member operatively connected thereto and adapted to be moved thereby to a position rearwardly of the plane of engagement of said elements and also rearwardly of the plane of the inner face of the slide whereby to deflect underlying material out of the path of said elements.

5. A slide fastener device comprising two series of mating fastener elements adapted to be secured along opposed edges of material to be joined together, a slide shiftable along said edges to engage said elements, and a shiftable handle connected to said slide, said handle having a guard member operatively fixed thereto and adapted to be moved thereby to a position rearwardly of the plane of engagement of said elements and also rearwardly of the plane of the inner face of the slide a substantial distance whereby to deflect underlying material out of the path of said elements.

6. A slide fastener device comprising two series of mating fastener elements adapted to be secured along opposed edges of material to be joined together, a slide shiftable along said edges to engage said elements, a shiftable handle connected to said slide and a guard member operatively pivoted to the handle and adapted to be moved thereby to a position rearwardly of the plane of engagement of said elements to deflect underlying material out of the path of said elements.

7. A slide fastener device comprising two series of mating fastener elements adapted to be secured along opposed edges of material to be joined together, a slide shiftable along said edges to engage said elements, a shiftable handle connected to said slide, and a guard member extended from the handle beyond the forward end of the slide and having a curved working end lying between said series of elements and movable rearwardly of the plane of engagement thereof and also rearwardly of the plane of the inner face of the slide when the handle is shifted to operative position.

8. A slide fastener device comprising two series of mating fastener elements adapted to be secured along opposed edges of material to be joined together, a slide shiftable along said edges to engage said elements, a shiftable handle connected to said slide and a guard member extending beyond the forward end of the slide and operatively connected to the handle and adapted to be moved thereby to a position rearwardly of the plane of engagement of said elements to deflect underlying material out of the path of said elements.

9. A slide fastener device comprising two series of mating fastener elements adapted to be secured along opposed edges of material to be joined together, a slide shiftable along said edges to engage said elements, and a handle for operating said slide and pivoted to the slide, said handle having a curved end lying forwardly of the slide.

10. A slide fastener device comprising two series of mating fastener elements adapted to be secured along opposed edges of material to be joined together, a slide shiftable along said edges to engage said elements, and a handle pivoted to the slide adjacent the forward end, said handle having a deflector guard normally lying beyond said forward end, said handle being shiftable to move said guard rearwardly of the plane of engagement of said elements.

11. A slide fastener device comprising two series of mating fastener elements adapted to be secured along opposed edges of material to be joined together, a slide member for engaging said elements, a handle member pivotally mounted upon said slide for moving the same, and a guard connected to the slide member and shiftable by said handle member into position rearwardly of the plane of the inner face of the slide member to displace material underlying said slide member to thereby prevent its being engaged by the fastener elements when the slide member is moved.

12. A slide fastener device comprising two series of mating fastener elements adapted to be secured along opposed edges of material to be joined together, a slide member for engaging said elements, and a handle pivotally connected to said slide member, said handle having a deflector guard, said guard being shiftable rearwardly of the plane of engagement of said elements when said handle is swung to operative position.

13. A slide fastener device comprising a pair of longitudinal strips provided with cooperating fastener elements on their adjacently disposed longitudinal edges, a slide member for operating said elements, and a deflector guard pivotally connected to said slide providing a handle for moving the same, said guard in its normal position lying substantially in the plane of the slide member and being shiftable relative to said slide into position rearwardly of the plane of the inner face of the slide member to displace material underlying the slide member to thereby prevent its being engaged by the fastener elements when the slide member is moved.

14. A slide fastener device comprising a pair of longitudinal strips provided with cooperating fastener elements on their adjacently disposed

longitudinal edges, a slide member for operating said elements, said slide member having grooves therein for receiving said fastener elements, and a deflector guard hingedly connected to said slide member having a handle portion for moving the slide, said guard normally lying substantially in the plane of the slide member and having a substantially hook-like lead portion integral with the handle portion and movable thereby into position substantially rearward of the plane of the inner face of the slide member to engage and displace material underlying the slide member to thereby prevent its being engaged by the fastener elements when said slide member is moved.

15. A slide fastener device comprising a pair of longitudinal strips provided with cooperating fastener elements on their adjacently disposed longitudinal edges, a slide member for operating said elements, said slide member having grooves therein for receiving said fastener elements, a deflector guard hingedly connected to said slide member and having a working end portion lying substantially in the plane of the slide member when in its normal position, said portion normally extending into the space between the fastener elements when in unlocked condition and movable into position to underlie said elements and the inner face of the slide member and displace material adjacent the underside of said member to thereby prevent its being engaged by the fastener elements when the slide member is moved.

16. A slide fastener device comprising a pair of longitudinal strips provided with cooperating fastener elements on their adjacently disposed longitudinal edges, a slide member having an aperture in its front face for operating said elements, a deflector guard pivotally connected to said slide providing a handle for moving the same, said guard being shiftable relative to said slide member into position to displace fabric underlying the slide member to thereby prevent its being engaged by the fastener elements when the slide member is moved, and means carried by said guard projecting through said aperture and engageable with the fastener elements to maintain the slide member in fixed position when said elements are in interlocked relation.

HOWARD BONBRIGHT.
